PORTABLE DRINK MIXER

Louis F. Danin, New York, N. Y., assignor to Kathi Urbach, Inc., New York, N. Y., a corporation of New York

Application February 23, 1955, Serial No. 34,632

Term of patent 3½ years

(Cl. D89—1)

The figure is an elevational view of a portable drink mixer, showing my new design.

The portions of the drink mixer not shown are like those shown except that the switch is omitted.

The characteristic features of my design for the mixer disclosed reside in the base portions having the configurations shown.

I claim:

The ornamental design for a portable drink mixer, substantially as shown and described.
